[57] **CLAIM**

The ornamental design for an instrument panel for an automobile radio and navigation system, as shown and described.

DESCRIPTION

FIG. 1 is a perspective view of an instrument panel for an automobile radio and navigation system according to our novel design;

FIG. 2 is a front elevational view thereof;

FIG. 3 is a right side elevational view thereof;

FIG. 4 is a left side elevational view thereof; and,

FIG. 5 is a top plan view thereof.

The dash lines shown depict environment and are not part of our claimed design.
